UNITED STATES PATENT OFFICE.

RICHARD W. REYNOLDS, OF KITTANNING, PENNSYLVANIA.

DOOR-MAT.

1,077,302.

Specification of Letters Patent.

Patented Nov. 4, 1913.

Application filed February 24, 1913. Serial No. 750,411.

To all whom it may concern:

Be it known that I, RICHARD W. REYNOLDS, a citizen of the United States of America, residing at Kittanning, in the 5 county of Armstrong and State of Pennsylvania, have invented certain new and useful Improvements in Door-Mats, of which the following is a specification, reference being had therein to the accompanying drawing.

10 This invention relates to door mats, and the primary object of my invention is to provide a sanitary mat by which mud, dirt and other foreign matter that ordinarily adheres to the soles of shoes can be expeditiously removed.

15 A further object of this invention is to provide a simple, durable and inexpensive door mat from which accumulated dirt and foreign matter can be easily removed, where- 20 by the mat can be repeatedly used for cleansing the soles of shoes.

25 With the above and other objects in view the invention resides in the novel construction, combination and arrangement of parts 25 to be hereinafter specifically described and then claimed.

30 Figure 1 is a perspective view of the mat. Fig. 2 is a plan of the same, Fig. 3 is a longitudinal sectional view of the mat, Fig. 4 35 is a cross sectional view of the same, and Fig. 5 is a plan of a portion of the mat.

35 A door mat in accordance with this invention comprises longitudinal parallel rails 1 and 2 connected at one end by transverse 40 scraper bars 3 and 4, said bars having the upper edges thereof beveled, with the bar 4 of greater elevation than the bar 3 whereby the sole of a shoe can be easily moved over said bars to scrape mud from the bottom of 45 the sole.

45 The rails 1 and 2 for the greater part of their length are connected by transverse parallel and equally spaced flat rods 5 and these rods are covered with a yieldable 50 cleansing material 6, as carpet, fiber or other fabric.

55 The inner sides of the rails 1 and 2 above the covered cleansing rods 5 are provided with longitudinal strips of fabric 7 similar 50 to that covering the rods 5, and while the covered rods permit of dirt being removed from the sole of the shoe, the strips of fabric 7 permit of the side edges of the sole and the heel being cleaned and polished.

55 Secured to the upper edge of the rail 1

by tacks 8, screws or other fastening means is one edge of a flexible holder 9 that forms the bottom of the mat. The holder 9 is preferably made of canvas or a durable fabric and extends around the outer side of 60 the rail 1 and upwardly against the outer side of the rail 2. The free edge of the holder 9 is provided with a case 10 containing a strip 11, this edge of the holder is held between two resilient clips 12 arranged at 65 the end of the rail 2.

The holder 9 collects dirt and foreign matter removed from shoes by the scraper bars 3 and 4, the covered rods 5 and the strips of fabric 7, and to clean the mat it is 70 only necessary to raise the same and open the holder 9. The mat can be beaten to remove dust from the covers of the rods 5 and the covers can be readily renewed without destroying the frame work of the mat. 75

It is thought that the utility of the mat will be apparent without further description and while in the drawing there is illustrated a preferred embodiment of the invention, it is to be understood that the structural ele- 80 ments are susceptible to such variations and modifications as fall within the scope of the appended claims.

What I claim is:—

1. A door mat comprising parallel side 85 rails, scraper bars connecting said rails at one end thereof, rods connecting said rails, fabric covers arranged upon said rods, and a flexible holder forming the bottom of said mat. 90

2. A door mat comprising parallel side rails, scraper bars connecting said rails at one end thereof, rods connecting said rails, fabric covers arranged upon said rods, and a flexible holder forming the bottom of said 95 mat and having one edge thereof permanently connected to one rail and the other edge detachably connected to the other rail.

3. A door mat comprising rails, transverse rods connecting said rails, fabric covers ar- 100 ranged upon said rods, and a movable flexible holder carried by said rails and forming the bottom of said mat.

In testimony whereof I affix my signature in the presence of two witnesses.

RICHARD W. REYNOLDS.
